UNITED STATES PATENT OFFICE.

GEORGE B. EHREMMAN, OF TROY, NEW YORK.

IRONING NECKBANDS.

1,384,605.

Specification of Letters Patent. Patented July 12, 1921.

Application filed May 8, 1919. Serial No. 295,542.

To all whom it may concern:

Be it known that I, GEORGE B. EHREMMAN, a citizen of the United States, residing at Troy, county of Rensselaer, and State of New York, have invented certain new and useful Improvements in Ironing Neckbands, of which the following is a specification.

Reference may be had to the accompanying drawings, and the reference characters 10 marked thereon which form a part of this specification. Similar characters refer to similar parts in the several figures therein.

This invention relates to the ironing of fabrics of various kinds, and the invention 15 may be carried out by various forms of ironing devices adapted for the particular work to be performed.

In the drawings, I have shown a preferred form of ironing mechanism particularly 20 adapted for ironing or smoothing the edges of neckbands, wrist-bands and the like.

The principal object of the invention is to quickly produce upon a fabric a polished or smooth surface.

25 Other objects will appear in connection with the following description.

Figure 1 of the drawings is a view in front elevation of my improved ironing machine.

30 Fig. 2 is a similar view of a broken-away portion of the same with the outer guide-flanges removed.

Fig. 3 is a similar view of the same with the main guides removed.

35 Fig. 4 is a view in end elevation of the machine shown in Fig. 1.

Fig. 5 is a view in perspective of the crank-mechanism whereby rapid reciprocating movements are imparted to the iron.

40 Fig. 6 is a view on a smaller scale similar to Fig. 1 showing the ironing apparatus mounted upon a standard.

Fig. 7 is a view similar to Fig. 3 with the face-plate of the combustion chamber re-45 moved.

Fig. 8 is a horizontal cross section taken on the broken line 8—8 in Fig. 7.

Fig. 9 is a view in perspective of the upper guiding-plate detached.

50 Fig. 10 is a similar view of the lower guiding-plate detached.

Fig. 11 is a view in perspective of the face-plate of the combustion chamber detached.

Fig. 12 is a view in perspective of the 55 iron, and lever whereby the iron is reciprocated.

Fig. 13 is a vertical longitudinal section through the same taken on the broken line 13—13 in Fig. 12.

Referring to the drawings wherein the invention is shown in preferred form, 1 is a standard upon the upper end of which is mounted a combustion chamber, 2, having a front face-plate, 3, formed with a curved 65 groove, 4, in its front face, from which a vertical groove, 5, extends to the top of the face-plate as shown in Fig. 11.

This face-plate is secured upon the front of the combustion chamber by screws, 6.

A lever, 7, is pivotally mounted at 8 within the groove, 5, which groove is of sufficient width to permit of limited reciprocating movement of said lever.

An iron, 9, is mounted upon the lower 75 end of said lever within the curved groove, 4, said curved groove being concentric with the pivotal connection, 8, of the lever, 7.

Reciprocating movement of the lever, 7, causes the iron, 9, to travel back and forth 80 within said curved groove, 4.

Reciprocating movements can be imparted to the lever, 7, by means of a crank-pin, 10, carried by a crank-disk, 11, mounted upon the shaft of an electric motor, 12, the casting of which is mounted upon the upper 85 end of the combustion chamber, 2.

The crank-pin, 10, plays in a slot, 13, in the upper end of the lever, 7, and is fixed upon a slide, 14, movable along a diametric 90 slot, 15, in the crank-disk, 11, and adapted to be secured in adjusted position in said slot by means of set-screws, 16, whereby the crank-pin, 10, can be located at different distances from the axis of the crank-disk, 11, to secure more or less throw of the lever, 7, and iron, 9.

By means of the electric motor, 12, rapid reciprocating movements may be imparted to the iron, 9.

100 Mounted upon the outer side of the face-plate, 3, by means of screws, 17, are an upper guiding-plate, 18, and a lower guiding-plate, 19, which form therebetween a guiding groove, 20, for a neckband or the like.

The neighboring ends of the guide-plates, 18 and 19, and the groove formed therebe-

tween, are curved in the arc of a circle concentric with the pivotal connection, 8, which forms the axis of reciprocating movement of the iron, 9.

5 The iron, 9, has in its face, a similarly curved groove, 21, the grooved face of said iron being complementary to said band-guiding mechanism and forming a bottom for the groove in said guiding mechanism.

10 The neighboring ends of the guiding plates, 18 and 19, are inclined inwardly toward each other as shown in Fig. 4, said ends thus converging inwardly toward the groove, 21, in the iron.

15 The guiding plates, 18 and 19, are adapted to receive between them a neckband, wristband or the like, and to form a guide for the same as the neck-band or wristband is drawn by hand along said groove, 20.

20 As an auxiliary guiding means for the neckband or the like, I mount upon the outer face of the guiding members, 18 and 19 respectively, plates, 22, each having a guide-flange, 23, with a space therebetween leading to the groove between the guiding plates, 18 and 19.

One or both of these plates, 22, may be made adjustable toward and from the other by means of a longitudinal slot, 24, adapted 30 to receive a pair of locking screws, 25.

For certain kinds of work these plates, 22, may be omitted.

The iron, 9, is adapted to be maintained in a heated condition during the ironing 35 operation by means of a gas-burner, 26, the flame from which is directed against the face-plate, 3, of the combustion chamber, 2, against which face-plate the iron, 9, rests.

A combustible mixture of gas and air may 40 be supplied to the gas-burner, 26, in any known manner.

For certain purposes of the invention, the heating mechanism may be omitted if desired, or any other known form of heating 45 mechanism may be used in place of that shown.

The preferred manner of operation of the machine is as follows.

The iron having been heated by means of 50 the burner, 26, is set in rapid vibration or reciprocation by the electric motor, 12, causing the iron to reciprocate rapidly through a path extending in the general direction of the groove, 20, between the guiding plates, 18 and 19. The neckband to be ironed is then inserted into said groove, 20, between the guiding plates, 18 and 19, until its edge 55 occupies the groove, 21, in the iron, 9.

The neckband is then progressively moved 60 along said groove, 21, while exposed to the rapidly reciprocating ironing movement of the iron, 9, which smooths and polishes the edge of the neckband.

While I have shown means for presenting 65 an article like a neckband edgewise to the

iron, I wish it understood that different kinds of work may be presented in a different manner to the iron.

The broadly characteristic feature of the invention is that the work is continuously 70 progressively moved relative to the iron while the iron is rapidly reciprocated in contact with the work, this characteristic feature being the same whether the work presents an edge or a flat surface to the iron. 75

For certain purposes of the invention, the groove, 21, in the iron may be omitted.

While I have shown an electric motor as a means for imparting rapid reciprocating movements to the iron, any other known 80 form of mechanism for imparting such reciprocating movements to the iron may be employed.

In imparting a relative progressive movement between the iron and the fabric, for 85 certain purposes of the invention it is immaterial whether the fabric be progressively moved relatively to the rapidly vibrating iron, or whether the rapidly vibrating iron also be progressively moved relatively to the 90 fabric.

By means of my invention, a smooth or highly polished surface can be imparted to fabrics of different kinds, and by the preferred form of apparatus shown, the edges 95 of neckbands and the like can be easily and quickly ironed smooth and relieved of the roughness which usually remains after the laundrying operation.

What I claim as new and desire to secure 100 by Letters Patent is—

1. In a machine of the class described and in combination, guiding mechanism forming a groove and provided with an opening in the groove-wall; an iron adjacent to said opening; and means for rapidly reciprocating said iron.

2. In a machine of the class described and in combination, guiding mechanism forming a curved groove adapted to receive a neckband or the like and provided with an opening in the groove-wall; an iron adjacent to said opening; and means for rapidly reciprocating said iron.

3. In a machine of the class described and in combination, guiding mechanism forming a curved groove in substantially an arc of a circle and provided with an opening in the groove-wall; an iron adjacent to said opening; an iron-carrying member pivotally mounted upon an axis substantially concentric with said circle; and means for rapidly oscillating said iron-carrying member and iron.

4. In a machine of the class described and in combination, a support provided with an opening therethrough; a pair of guide-members mounted with capability for relative adjustment with a band-guiding groove between said members; an iron reciprocating 125

ingly movable in said opening in the support; and means for rapidly reciprocating said iron.

5. In a machine of the class described and in combination, band-guiding mechanism formed with a groove adapted to receive a neckband or the like said groove being formed with a bottom opening; an iron mov-

able in said opening and having a grooved face complementary to said band-guiding mechanism; and means for rapidly reciprocating said iron in a path corresponding with the groove in said guiding mechanism.

In testimony whereof, I have hereunto set my hand this 24th day of April, 1919.

GEO. B. EHRMANN.
